UNITED STATES PATENT OFFICE.

BERT NILES, OF TYRE, MICHIGAN.

BREAK-DETECTOR FOR BINDERS.

1,288,654.

Specification of Letters Patent.

Patented Dec. 24, 1918.

Application filed December 12, 1917. Serial No. 206,798.

To all whom it may concern:

Be it known that I, BERT NILES, a citizen of the United States, residing at Tyre, in the county of Sanilac and State of Michigan, have invented a new and useful Break-Detector for Binders, of which the following is a specification.

This invention relates to a break detecting attachment for binders, one of the objects of 10 the invention being to provide a detecting device which can be applied readily to a binder and which will, in event of the breaking of the twine, immediately sound an alarm so that the operator can stop the machine and repair the damage.

A further object is to provide a device of this character which can be installed in a machine without making any changes in the construction or arrangement of the parts al-

20 ready in use.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, can be made within the scope of what is claimed, without departing from the spirit of the invention.

In the accompanying drawing, which is 30 a perspective view of a portion of a binder with the present improvements combined therewith, the preferred form of the invention has been shown.

Referring to the drawing by characters of reference B designates a twine box or holder such as ordinarily used in a binder and the twine T extends therefrom through suitably 35 arranged guides G to the needle N. S designates a shaft arranged close to the needle and which forms a part of a binder.

The attachment constituting the present invention comprises a bell crank lever 1 one arm of which has an eye 2 through which 40 twine T extends. The arm of this lever carries a revoluble bell 3 which can be provided

with a roller 4. A spring 5 is connected to one arm of the bell crank lever and tends to pull said lever into position to cause the 50 roller 4 to engage a wheel 6 secured to the shaft S. The twine T, however, by extending through one arm of the lever, prevents the lever 1 from being shifted by the spring 5 under normal conditions. Consequently as 55 long as the twine is unbroken and in use it will remain taut and hold the spring 5 under tension. When the twine breaks, however, spring 5 will promptly shift the lever 1 so as to bring the roller 4 against the wheel 6 60 and cause the bell 3 to be sounded. Obviously instead of providing the roller 4, said bell can be caused to directly engage the shaft S and be rotated thereby. Such modification is so obvious that it is not deemed 65 necessary to illustrate it.

What is claimed is:—

1. In a binder the combination with a needle and means for supplying twine thereto and a revoluble member adjacent the 70 needle, of a detector including a lever slidably engaged and held against movement by the twine extending through the needle, a revoluble alarm device carried by the lever, and means for shifting said alarm device 75 against said revoluble member when the twine breaks, to sound the alarm.

2. In a binder the combination with a needle, means for supplying twine thereto, and a revoluble member adjacent to the 80 needle, of a lever slidably engaged and held against movement by the twine, a revoluble alarm device carried by the lever, and a spring carried by the lever for shifting the alarm device into position for actuation by 85 the revoluble member when the twine is broken.

In testimony that I claim the foregoing as my own, I have hereto affixed my signature in the presence of two witnesses.

BERT NILES.
